Primary Examiner — Ramzi Almatrahi(74) *Attorney, Agent, or Firm* — Capitol City TechLaw(57) **CLAIM**

The ornamental design for a lens for image inspection camera, as shown and described.

DESCRIPTION

FIG. 1 is a front, top, and right side perspective view of a lens for image inspection camera showing my new design; FIG. 2 is a front, top, and left side perspective view thereof; FIG. 3 is a front, bottom, and left side perspective view thereof;

FIG. 4 is a front view thereof;

FIG. 5 is a rear view thereof;

FIG. 6 is a left side view thereof;

FIG. 7 is a right side view thereof;

FIG. 8 is a top view thereof; and,

FIG. 9 is a bottom view thereof.

The broken lines depict portions of the lens for image inspection camera in which the design is embodied that form no part of the claimed design. Additionally, the dash-dot lines denote the boundary of the claim and form no part of the claimed design.
